Edgar Date & Co

UNITED STATES PATENT OFFICE.

JOSEPH McCRINK, OF NEWARK, NEW JERSEY.

BOTTLE PROTECTOR.

Application filed August 30, 1922. Serial No. 585,123.

To all whom it may concern:

Be it known that I, JOSEPH McCRINK, a citizen of the United States, and residing at Newark, in the county of Essex and State of New Jersey, have invented certain new and useful Improvements in Bottle Protectors, of which the following is a specification, such as will enable those skilled in the art to which it appertains to make and use the same.

This invention relates to protectors for bottles of various kinds and classes and particularly to what are known as nursing bottles, and the object of the invention is to provide a protector composed of openwork, resilient material adapted to be mounted on the bottle to prevent or avoid the breaking of such bottle in the event of its being dropped onto a floor or pavement or hit against hard bodies; a further object being to provide a protector of the class specified with means for protecting the neck portion of the bottle, said bottle being insertable into the protector through the bottom thereof and being retained therein by resilient members at the bottom of the protector; a still further object being to provide a flat bottom for the protector whereby the nursing bottle may be supported in an upright position on a table or other support, and with these and other objects in view the invention consists in a device of the class and for the purpose specified which is simple in construction, efficient in use and which is constructed as herein-after described and claimed.

The invention is fully disclosed in the following specification, of which the accompanying drawing forms a part, in which the separate parts of my improvement are designated by suitable reference characters in each of the views, and in which:—

Fig. 1 is a side view of a nursing bottle with one of my improved protectors mounted thereon with parts of the construction broken away and in section.

Fig. 2 is a partial section on the line 2—2 of Fig. 1; and,

Fig. 3 is a partial section on the line 3—3 of Fig. 2.

In the construction shown in the accompanying drawing, my improved protector comprises a unitary cage-like structure 5 composed of a plurality of annular bands 6, 7, 8, 9 and 10, the band 6 being the bottom band and the band 10 the top band, and these bands are joined by vertical rib members 11,

four of which are shown but any number of which may be employed.

The band 6 and rib members 11 are all composed of resilient material such as rubber or a rubber composition and the bottom band 6 is provided on its inner face with a ridge 12 forming a seat for a nursing bottle 13, and at predetermined points preferably in line with the ribs 11 are inwardly projecting keepers 14, which are adapted to extend beneath the bottom of the bottle 13 as clearly shown in Figs. 1 and 3.

The bands 6, 7 and 8 are substantially of the same dimensions while the bands 9 and 10 are of less dimensions than the bands 6, 7 and 8 and are adapted to fit around the neck of the bottle, the band 9 fitting snugly around the neck while the band 10 is preferably free from the neck or upper end portion of the bottle and it is preferred that the band 10 extend slightly above the top or upper end of the bottle proper so as to protect the bottle against breakage if it should strike a floor or the like on its upper end. It will also be noted that the rib members 11 which join the bands 9 and 10 or one of said rib members may be used for the purpose of attaching a cord or the like 15 for securing the protector to a predetermined support, as for example, to a baby carriage.

In the use of my improved protector, a nursing bottle 13 is inserted into the protector through the bottom ring 6 thereof and forced upwardly through the protector or the separate rings 7, 8, 9 and 10 thereof into the position shown in Fig. 1 in which position, the members 14 will spring beneath the bottom of the bottle and serve to retain the bottle in the protector. In removing the nursing bottle from the protector, the above operation is reversed and the bottle is forced downwardly through the bottom of the protector, and it will be understood that while I have shown a specific form of protector and of specific design, that I am not necessarily limited in these respects, and various changes in and modifications of the construction herein shown and described, may be made within the scope of the appended claims, without departing from the spirit of my invention or sacrificing its advantages.

Having fully described my invention, what I claim as new and desire to secure by Letters Patent, is:—

1. A bottle protector of the class described,

- comprising a cage-like structure of unitary construction and consisting of a bottom ring member, a top ring member, intermediate ring members spaced apart by vertical rib members, and said bottom ring member being provided with a plurality of inwardly projecting retaining members.
2. A bottle protector of the class described, comprising a cage-like structure of unitary construction and consisting of a bottom ring member, a top ring member, intermediate ring members spaced apart by vertical rib members, and said bottom ring member being provided with a plurality of inwardly projecting retaining members and with an annular retaining seat.
3. A bottle protector of the class described, comprising a cage-like structure of unitary construction and consisting of a bottom ring member, a top ring member, intermediate ring members spaced apart by vertical rib members, said bottom ring member being provided with a plurality of inwardly projecting retaining members and with an annular retaining seat, and the top ring member being of less dimensions than the bottom ring member.
4. A bottle protector of the class described, comprising a cage-like structure of unitary construction and consisting of a bottom ring member, a top ring member, intermediate ring members spaced apart by vertical rib members, said bottom ring member being provided with a plurality of inwardly projecting retaining members and with an annular retaining seat, and the top ring member being of less dimensions than the bottom ring member; and the ring member adjacent to said top ring member being of substantially the same dimensions as said top ring member.
5. A nursing bottle protector of the class described, comprising a unitary cage-like resilient body consisting of a plurality of annular ring members joined and spaced by vertical rib members, and the nursing bottle to be protected being adapted to be inserted into the protector through the bottom ring member, means for retaining the nursing bottle in the protector, and said bottom ring member being provided with a flat face to permit of the supporting of said bottle and protector in an upright position.
6. A nursing bottle protector of the class described, comprising a unitary cage-like resilient body consisting of a plurality of annular ring members joined and spaced by vertical rib members, and the nursing bottle to be protected being adapted to be inserted into the protector through the bottom ring member, means for retaining the nursing bottle in the protector, said bottom ring member being provided with a flat face to permit of the supporting of said bottle and protector in an upright position, and the top ring member of said protector extending above the top of the bottle to be protected.
7. A nursing bottle protector of the class described, comprising a unitary cage-like resilient body consisting of a plurality of annular ring members joined and spaced by vertical rib members, and the nursing bottle to be protected being adapted to be inserted into the protector through the bottom ring member, means for retaining the nursing bottle in the protector, said bottom ring member being provided with a flat face to permit of the supporting of said bottle and protector in an upright position, and the top ring member of said protector extending above the top of the bottle to be protected, and being of less dimensions than the bottom ring member.
8. A nursing bottle protector of the class described, comprising a unitary openwork body of resilient material fashioned to conform substantially with the form of a nursing bottle, and comprising a plurality of ring members adapted to encircle the body of the bottle and other ring members adapted to encircle the neck and top portion of the bottle, said ring members being joined by vertical rib members, and the top ring member projecting beyond the top of the bottle.
9. A nursing bottle protector of the class described, comprising a unitary openwork body of resilient material fashioned to conform substantially with the form of a nursing bottle, and comprising a plurality of ring members adapted to encircle the body of the bottle and other ring members adapted to encircle the neck and top portion of the bottle, said ring members being joined by vertical rib members, and the bottom ring member extending below the bottom of the bottle and being provided with inwardly projecting resilient retaining members.
- In testimony that I claim the foregoing as my invention I have signed my name this 28th day of August, 1922.

JOSEPH McCRINK.
